UNITED STATES PATENT OFFICE.

ROBERT H. PFLUGFELDER, OF CHICAGO, ILLINOIS.

REMOVING ALCOHOL FROM LIQUORS.

1,249,480.

Specification of Letters Patent. Patented Dec. 11, 1917.

Application filed May 29, 1917. Serial No. 171,750.

To all whom it may concern:

Be it known that I, ROBERT H. PFLUGFELDER, a citizen of the United States, residing at Chicago, in the county of Cook and State of Illinois, have invented certain new and useful Improvements in Removing Alcohol from Liquors, of which the following is a specification.

My invention relates to a process and apparatus for removing alcohol from liquors and has for its primary object the provision of an improved process and apparatus whereby the liquor, after having the alcohol removed, shall remain free from the well known burnt taste commonly found in de-alcoholized liquors where the heating agency for vaporizing the alcohol is steam.

A further object of the invention is the provision of a process by the use of which less fuel is required than is necessary where steam or other equal heat media are employed.

Other objects and advantages of the invention will appear from the following description taken in conjunction with the accompanying drawings which form a part of this specification.

In the drawings

Figure 1 is a section taken substantially on line 1—1 of Fig. 3;

Fig. 2 is a section taken substantially on line 2—2 of Fig. 1; and

Fig. 3 is a section taken on line 3—3 of Fig. 1.

Reference numeral 10 indicates the body portion of a large tank preferably rectangular in cross-section, provided with a cone shaped cover 11 secured to the tank by a fluid tight joint and communicating at its top with the pump, generally indicated at 12, for withdrawing vaporized alcohol from the tank.

Secured within the tank are a plurality of superposed downwardly slanting brackets 13 each of which supports a coil of hot water pipes 14, alternate brackets being oppositely slanted, and all of the brackets terminating short of the opposite wall from that to which they are fastened.

As best illustrated in Fig. 2, the apparatus is provided preferably with two circulating coils. Hot water enters the coils from a hot water main 15 and is discharged through a heat exhaust pipe 16. The main 15 carries a branch 17 which feeds hot water

to the upper coil 18 and a lower branch 19 which feeds hot water to the lower coil 21. The exhaust pipe 16 has an upper branch 22 which drains the upper coil 18 and a lower branch 23 which drains the lower coil 21. Resting upon the hot water coils in the tank 10 are liquor pans 24 slanting in parallelism with the brackets 13 and adapted to deliver liquor from one to another in a zigzag course downwardly through the tank, as best seen in Fig. 1, each of these pans being upturned at its higher end as at 25 and down turned at its lower end as at 26, the slant of the pans being such as to cause liquor delivered to the uppermost pan through a delivery pipe 27 to trickle slowly over the pans 24. From the lower pan 24 the de-alcoholized liquor drops to the bottom of the tank, where it collects in a body, indicated at 28, and is drawn off at suitable intervals through a discharge pipe 29, by means of any suitable pump 31. The delivery pipe 27 is as long as the breadth of the pans 24 and is apertured at spaced intervals as at 32 to provide for delivery liquor across the whole width of the pan. Preferably the pans have an area somewhat less than the cross-sectional area of the tank 10, in order to provide room on three sides between the edge of the pan and the wall of the tank for the operator to pass about the apparatus in cleaning it. Entrance into the tank is had through any suitable manhole provided with a door 34 clamped into position in any suitable manner, as, for instance, by means of the yoke 35 and bolt 36.

In the operation of my invention hot water, preferably at a temperature of 135 degrees Fahrenheit or thereabouts, is passed through the pipes 14 of the coils 18 and 21 and caused to flow continually therethrough. Beer, or any other alcoholic liquor, is now fed onto the upper pan 24 through the apertures 32 of feed pipe 27. The liquor flows down the heated pans in section and finally drops from the lowest one to the bottom of the tank, whence it may be drawn off by the pump 31. The low inclination of the pans 24 causes the liquor to travel slowly over the heated pans and a sufficient number of pans are provided to make the path of travel of the liquor sufficiently long to vaporize all the alcohol. The vaporized alcohol is drawn off from the top of the cover 11 by means of the pump 12. By employ-

ing water at substantially 135 degrees temperature I accomplish the removal of the alcohol from the liquor while leaving the resulting liquor free from any taste of 5 steam, and the low temperature at which the alcohol is removed greatly reduces the amount of fuel needed inasmuch as no steam pressure is required.

While I have illustrated and described 10 the preferred embodiment of my invention, it will be obvious that one skilled in the art may make modifications thereof without departing from the spirit of the invention. I wish, therefore, not to be restricted to the 15 precise embodiment shown except in so far as the same is limited in the appended claims.

The tank 10 is air tight and the interior pressure is kept below atmospheric pressure 20 by pump 12. In this way the alcohol is evaporated from the beer at a temperature less than that required under full atmos-

pheric pressure so that conservation of fuel and rapid operation result.

I claim:

In an apparatus for removing alcohol from liquors the combination with a deep tank of superposed brackets secured alternately to opposite sides of the interior of the tank and slanting downwardly from the 8 wall of the tank, each of said brackets being spaced from those nearest it and terminating at a point remote from the wall opposite to that from which it is supported, heating pipes traversing said brackets, and 3 pans disposed upon said pipes, said pans being adapted to carry a stream of liquor and deliver the same from one pan to the next, the pans being of somewhat less area than the cross-sectional area of the tank. 4

In testimony whereof I have affixed my signature.

ROBERT H. PFLUGFELDER.
